UNITED STATES PATENT OFFICE.

ALBERT E. EVANS, OF PITTSBURGH, PENNSYLVANIA, ASSIGNOR TO PITTSBURGH PLATE
GLASS COMPANY, A CORPORATION OF PENNSYLVANIA.

FLUID-COOLED ROLL.

Application filed September 11, 1923. Serial No. 663,051.

The invention relates to fluid cooled rolls, and is designed particularly for use in apparatus for continuously rolling a glass sheet such as illustrated and described in the application of Frederick Gelsthar, Serial No. 656,441, although the roll construction is not limited to use in this particular relation. In apparatus for rolling glass, in which fluid cooled rolls are employed, it is desirable that the rolls should be cooled uniformly, as otherwise the rolls will soon be warped out of shape so that it is impossible to produce a sheet of uniform thickness, and furthermore the application of a non-uniform cooling effect on the glass sheet or ribbon being formed introduces strain into the sheet, increasing the breakage. One object of the present invention is the provision of improved means for securing a uniform cooling effect throughout the length of the roll. Further objects of the invention are (1) the provision of rolls which may be made without difficulty, (2) which are of simple construction, and (3) in which a substantial part of the construction is capable of reuse after the outer portion of the roll is worn so that it is not suitable for further service. One embodiment of the invention is illustrated in the accompanying drawings wherein:

Figure 1 is a longitudinal section through the roll. Fig. 2 is a section through the ends of the roll on a larger scale than Fig. 1. Fig. 3 is a side elevation of the core which fits into the cylindrical casing. Figs. 4 and 5 are end elevations of the roll. Figs. 6 and 7 are sections on the lines V—V and VI—VI respectively of Fig. 1. And Figs. 8, 9 and 10 are detail views of the cage constituting a part of the stuffing box construction at each end of the roll.

The roll consists of a cylindrical casing 1, a core 2 which is circular in cross section and fits snugly into the casing, the swivels 3 and 4 at the ends of the rolls, and a stuffing box construction for use in connection with the swivels. The roll is designed to be used in conjunction with another similar roll for providing a pass therebetween, and the dotted line figure marked 5 indicates the cross section of the sheet of glass which is to be formed by the rolls.

The core 2 is provided with the plurality of grooves 6 extending longitudinally thereof. At one end, these grooves terminate short of the end of the core as indicated at 7, while at

the other end they extend clear to the end of the core as indicated at 8. The latter end of the core is provided with a part 9 of reduced diameter for the purpose of providing a support for a packing gland as hereinafter set forth. The core 2 is held against rotation with respect to the casing 1 by means of a pin 10 which has a driving fit in suitable perforations extending through the core and casing. The roll is rotated by means of a wobbler 11 which is screw threaded into the right hand end of the casing and is held against turning by means of a pin 12 which has a driving fit in suitable perforations extending through the casing and wobbler.

The swivel 4 has an inlet connection 13 and an outlet connection 14 communicating with the annular passages 15 and 16 respectively and these annular passages are adapted to communicate with perforations 17 and 18 extending through the casing. As indicated in Fig. 7, the perforations 18 communicate with alternate ones of the grooves 2. The other set of perforations 17 communicate with the other grooves 2. The swivel 3 at the other end of the roll is similar in construction to the swivel 4 and has an inlet 19 and a outlet 20 communicating with annular passages 21 and 22 which in turn communicate with perforations 23 and 24 extending through the wall of the casing 1. The perforations 23 communicate with the same grooves 2 with which the perforations 18 at the other end of the casing communicate, while the perforations 24 communicate with the same grooves with which the perforations 17 communicate at the other end of the casing. Suitable supply pipes are coupled to the inlets and outlets so that, when in use, a cooling fluid such as water passes in through the inlet 13 along the grooves 6 and out at the outlet 20, while a second flow of water passes in through the inlet 19, along the alternate grooves 6 and 100 out at the outlet 14. A flow of cooling liquid is thus provided in the alternate grooves in opposite directions, thus tending to give a more uniform cooling than if the liquid all passed through in the same direction, in which case the roll would be cooled to a greater extent at the inlet end.

Suitable packing for the swivel 4 is provided by the packing rings 25, 26 and 27 pressed forward by means of the gland 28.

The gland itself is adjusted by means of the screws 29 extending through the ring 30, and this ring is secured to the end of the casing by means of the set screws 31. In order to apply pressure from the rings 27 to the rings 26, an annular cage or follower 32 shown in detail in Figs. 8, 9, and 10 is preferably employed, such cage consisting of the rings 33 and 34 connected by the bars 35. This cage or follower, by reason of its skeleton formation, permits a free flow of liquid through the annular passage 16 and to the various perforations 18. The ring portion 34 is provided with a pair of screw threaded cavities 36 into which a tool may be screwed when it is desired to withdraw the cage from its position of use inside the swivel.

The arrangement for packing the swivel at the left hand end of the casing is the same as that just described in connection with the swivel 4 so that no further description is necessary. In order to pack the ends of the grooves 6 at the left hand end of the core, the gland 37 is employed, such gland being forced into position by means of the bolt 38 threaded into the projection 9 on the end of the core. Suitable packing rings 39 are employed intermediate the end of the gland and the ends of the grooves 6.

The parts may be readily assembled and dis-assembled and the cooling of the roll is secured by reason of the flow of cooling

liquid through the grooves in opposite directions so that any warping of the roll due to uneven cooling is avoided. When the casing 1 becomes worn to such an extent that it is unsuitable for further use, a duplicate casing is supplied with which the core and swivels may again be used, if the core is not too tightly held in the casing, a tight fit being insured by shrinking the casing onto the core. The gland 37 gives access to the ends of the grooves 6 for cleaning, and if desired these grooves might be extended clear to the other end of the core and a gland provided there so as to give still greater accessibility to the grooves for cleaning purposes.

What I claim is:

In combination in a roll, an outer cylindrical casing, a core adapted to fit in such casing and having its surface provided with grooves extending longitudinally thereof parallel with the axis of the roll, and a swivel at each end of the casing, each of which has an inlet connection communicating with alternate grooves and an outlet connection communicating with the remainder of the grooves, whereby a circulation of cooling fluid may be provided in both directions through the roll.

In testimony whereof, I have hereunto subscribed my name this 29 day of Aug., 1923.

ALBERT E. EVANS.
